UNITED STATES PATENT OFFICE

CHRISTIAN MAJER, OF TUBINGEN, GERMANY

PROCESS AND APPARATUS FOR PRODUCING PAPER SLEEVES AND COILS WITH REINFORCEMENTS WOUND AROUND

Application filed July 30, 1928, Serial No. 296,386, and in Germany June 25, 1926.

This invention relates to a method and an apparatus for producing paper sleeves and bobbins with reinforcements of any kind, consisting of wound up paper strips. The method is characterized in that the paper strips are cut from an endless paper band fed by means of lateral devices to the paper sleeves wound on the winding spindles. In this case oblique strips must be cut off the paper band.

The devices for feeding the strips consist of oscillatable arms, levers or slides, which insert the paper strip under the last winding of the sleeve. On the conveying devices brakes are provided which conduct the strip by stronger braking on the outer side towards the inner guide, whereby a winding is obtained which is accurately uniformly superposed so that a quite smooth end face of the reinforcement is obtained.

The method and the apparatus for producing paper sleeves with wound-up reinforcements are illustrated, by way of example, in the accompanying drawing in which:

Fig. 1 shows the apparatus in cross section.

Fig. 2 is a top plan view of Fig. 1.

Figs. 3 and 4 show details of the feeding device on larger scale.

Fig. 4^a shows by way of example a sleeve made on the apparatus.

The strips 7 are periodically severed from the end of the paper-band 1 and fed by the device 2 to the winding spindles 3. As shown in the drawing the strip feeding devices consist of oscillatable arms 4, carrying at their ends guide-plates 5, 6 between which the paper strips are guided. On the guide plates brakes 8 of any suitable construction are arranged and designed to exert a braking action on the strip 7 at the winding up. The brake 8 is constructed so that it exerts a stronger pressure on the outer edge of the strip whereby this strip is permanently pressed against an inner guide 10, so that an accurately uniform winding of the strip and a smooth end-face of the same are obtained.

The feeding of the strip 7 to a sleeve 11 takes place at the moment before the end 12 of the sheet designed to form the sleeve has been wound up. The projecting portion of

strip 7 is gripped between the end 12 of the sleeve sheet and a sleeve 13 so that the strip 7 is wound around the sleeve. The sleeves 11 as shown in Fig. 4^a have conical reinforcements. In this case oblique strips must be cut off the paper band.

In order to avoid waste of paper the strips 7 are cut alternately inclined obliquely to the right and to the left and fed to the winding spindles 3 by the feeding devices 2 from both sides.

The guides 5, 6 with the brake 8 may be oscillatable when mounted on an arm 4, or stationary without the arm 4.

The severed strips 7 may be inserted into the guides 5, 6 mechanically or by hand.

Instead of providing a winding spindle 3 on each side of the paper sheet only one winding spindle 3 may be arranged on one side.

If sleeves with conical reinforcements, as shown in Fig. 4^a, have to be produced the winding spindles must be arranged on both sides and the strips cut as shown in Fig. 1, as they are cut obliquely in opposite directions.

For producing sleeves with cylindrical reinforcements the winding devices 4, 5 and 3 are arranged only on one side.

The strips 7 might be cut preliminarily and then inserted into the guides 5, 6 by hand or with the aid of a mechanical device.

The brake 8 may consist, instead of a brake shoe controlled by a blade spring 9, of a movable brake block forming an arm and the like.

To facilitate the insertion of the strip 7 into the guides 5, 6 and under the brake shoe 8, the upper guide 6 which carries the brake shoe 8 may be arranged so that it can be intermittently lifted or oscillated.

The winding up strip 7 is held by a separate holder until the projecting front end has been gripped by the end 12 of the sleeve sheet, said strip being then wound around the sleeve 11 under the action of the brake. The device may otherwise be constructed in any suitable manner.

I claim:

1. A feeding device for feeding severed

paper strips to a winding spindle for winding said strips around the strip wound on said winding spindle consisting of an oscillatable arm and of two guides on said arm for conducting the paper strip periodically to a winding spindle.

2. A device for feeding a severed paper strip to a winding spindle for winding said strip around the strip wound on said winding spindle, comprising in combination an oscillatably mounted arm, periodically oscillated, a lower guide plate on the end of said arm, an upper guide plate on the end of said arm spaced a certain distance from said lower guide plate, a guide at the side of said guide plates, a brake extending through said upper guide plate, and a blade spring acting upon said brake so that said brake exerts a stronger pressure on the outer edge of said paper strip than on the inner edge of the same to permanently press said paper strip against said lateral guide.

In testimony whereof I affix my signature.
CHR. MAJER.
